UNITED STATES PATENT OFFICE

2,096,897

SHADE PULL

Walter Herrmann, Chicago, Ill., assignor to E. L. Mansure Co., Chicago, Ill., a corporation of Illinois

Application July 27, 1934, Serial No. 737,146

5 Claims. (Cl. 156—40)

This invention relates to a shade pull, and a primary object of the invention is the provision of a device of this character, economical to manufacture, extremely durable and efficient in operation and neat and attractive in appearance.

A further object resides in providing a shade pull comparatively plain in appearance and form so as to eliminate expensive and tedious operations, such as crocheting, for covering previous 10 types of shade pulls, which will not gather dust or become soiled to an appreciable degree over a long period of time and which is extremely easy to clean.

Other objects will appear hereinafter.

15 The invention consists in the combinations and arrangements of parts, hereinafter described and claimed.

The invention will be best understood by reference to the accompanying drawing which forms 20 a part of this specification, and in which:

Fig. 1 is a front elevational view of the article of the invention operatively connected to a roller shade;

Fig. 2 is a side elevation of the device shown in 25 Fig. 1;

Fig. 3 is a plan view of a strand of material which may be advantageously used to form the main body portion of the device, centrally cut away to illustrate the interior construction;

30 Fig. 4 is a plan view of the strand of the main body portion after the first bending operation in the process of manufacture in which the central portion is bent to form a curve preparatory to final bending operation which provides a loop formation;

Fig. 5 is a view of the final position of the strand or main body portion after the ends have 35 been bent inwardly and placed in juxtaposed relation;

40 Fig. 6 is a top plan view taken on the line 6—6 of Fig. 5;

Fig. 7 is a perspective view of the securing end closure clip or cap adapted to embrace and secure the exposed ends of the strand following the final 45 formation shown in Fig. 5;

Fig. 8 is a view of the device with the closure and securing clip applied and prior to the clinching operation;

Fig. 9 is a view, similar to Fig. 8, showing the 50 device after the clinching operation in which the closure clip is clinched centrally and longitudinally to tightly engage the ends of the main body strand;

Fig. 10 is a plan view taken substantially on the 55 line 10—10 of Fig. 9;

Fig. 11 is a horizontal sectional view taken substantially on the line 11—11 of Fig. 9; and

Fig. 12 is an enlarged vertical sectional view taken substantially on the line 12—12 of Fig. 10.

Referring to the drawing, the preferred embodiment of the device comprises a main member or strand 15 of flexible material capable of being bent into the formation disclosed. In actual practice it has been found that a strand approximately five-sixteenths of an inch in diameter and 10 approximately four and five-eighths of an inch in length provides a pull of proper size, although it will be understood that these dimensions may be varied as occasion or preference might require.

In order to obtain both flexibility and a certain 15 degree of resiliency in the pull loop, a material that has been found eminently suitable for the purpose is the present type of high tension insulated wire used for ignition purposes in automobiles. This material eliminates the objectionable clicking sound produced by materials such as metal, celluloid, bakelite or the like, when the pull is dropped or blown against a window pane. This material comprises a central twisted copper 20 wire core 16, covered by a rubber or resilient composition 17 and having a tightly woven braided covering 18 finished with a coating of shellac. This high tension wire may be then covered with a braid of cotton, silk or other textile material to give a finished appearance.

After the strand has been formed as shown in 25 Fig. 5 to provide a lower curved portion 19 and converging intermediate portions 20 and 21, terminating in juxtaposed end portions 22 and 23 respectively, the closure end securing clip 24 is 30 applied.

The closure end securing clip 24 is generally 35 elliptical in cross section as shown in Fig. 7, is provided with an upper closed end and a lower open end whereby the member may be slid over 40 the ends 22 and 23 to the position shown in Fig. 8, and the member is preferably chromium or nickel plated to enhance durability and appearance. After this operation the member 24 is 45 preferably tightly locked in engagement by a clinching operation on opposite sides 25 and 26 to produce a longitudinal depression upon the opposite sides.

For securing the pull to a connecting cord, the closed end of member 24 may be provided with an 50 opening 27. An open-eye needle carrying a looped connecting cord 28 is forced between strand ends 22 and 23, which is feasible because of the resilient and compressible character of the strand material, and cord 28 is then pulled through opening 55

27 to bring the knotted extremity 29, which is larger than opening 27, in contact with the inner surface of the closed end of member 24. These parts then assume the relative positions shown in 5 Fig. 12 and it will be noted that the convex surface of the closed end of member 24 serves to provide a space 30 for knot 29. This manner of attachment is exceptionally competent and efficient for the purpose and eliminates unsightly exterior knots or other fastening means.

10 The device is then secured to the shade by passing the closed end of cord 28 through eyelet 31 and then passing the device through the closed end to bring the cord and pull in the position 15 shown in Figs. 1 and 2, in the usual manner. It will be understood that the invention is not necessarily confined to the particular loop construction disclosed and described but may be varied by adopting other curved or polygonal formations.

20 While I have illustrated and described the preferred form of construction for carrying my invention into effect this is capable of variation and modification without departing from the sphere of the invention. I therefore do not wish to be 25 limited to the precise details of construction set forth, but desire to avail myself of such variations and modifications as come within the scope of the appended claims.

Having thus described my invention, what I 30 claim as new and desire to secure by Letters Patent is:

1. A shade pull of the character described,

comprising a strand of flexible material bent to bring the ends in juxtaposed relation, and a closure and securing member for said ends, said strand having a resilient covering.

2. A shade pull comprising a section of wire 5 having a resilient coating and bent to form a loop with its ends in parallel relation, an ornamental woven covering for said loop, a ferrule clamped upon said parallel ends, and a cord secured to said ferrule for attaching said device to a window shade, substantially as described.

3. A device as set forth in claim 2 further characterized by a transparent dirt resisting, waterproof coating for said loop, substantially as 15 described.

4. A shade pull comprising a section of heavily insulated wire bent to form a loop with its ends in parallel relation, a ferrule enclosing and securing said ends, an ornamental covering for said loop, a coating of transparent dirt resisting material for said ornamental covering and a cord secured to said ferrule for attaching the device to a window shade, substantially as described.

5. A shade pull comprising a section of heavily insulated wire bent to form a loop with its ends in parallel relation, a ferrule enclosing said ends and clamped upon the same, an ornamental covering for said loop and a coating of flexible transparent dirt resisting material for said loop, substantially as described.

WALTER HERRMANN.
